FET FLIP-FLOP DRIVING CIRCUIT

This invention relates to a circuit for driving a flip-flop constituted by insulated gate field effect transistors.

It has been attempted to constitute a flip-flop circuit by the use of insulated gate field transistor devices such for example as metal-insulator-semiconductor field effect transistors (referred to as MIS transistor hereinafter). An example of such flip-flop circuit is disclosed in U.S. Pat. No. 3,363,115, for example. Advantageously, the MIS transistor can easily be integrated in a single semiconductor substrate, and the power consumption thereof is low because of the voltage-controlled type. Therefore, a flip-flop using such MIS transistors is also advantageous.

The inventor has observed the fact that erroneous operation is often caused when such a flip-flop as disclosed in the said patent is driven, and found that this is due to an undesirable timing relationship between a first pulse signal provided by a pulse source and a second pulse signal (inverted signal of said first signal). This will be more fully described hereinafter with reference to the drawings.

It is an object of the present invention to provide a driving circuit capable of preventing erroneous operation of a flip-flop constituted by insulated gate field effect transistors.

Another object of the present invention is to provide a transistorized flip-flop which can be operated with a low-voltage source.

A still another object of the present invention is to provide a flip-flop circuit arrangement which can easily be realized by the semiconductor integrated circuit technique.

Other objects, features and advantages of the present invention will become apparent from the following description taken in conjunction with the accompanying drawings, in which

FIGS. 1 and 10 are circuit diagrams showing flip-flop constituted by insulated gate-type field effect transistors, respectively;

FIG. 2 is a view showing input and output signal waveforms occurring in said flip-flops;

FIG. 3 and 4 are a schematic sectional view showing insulated gate-type field effect transistors incorporated in a semiconductor integrated circuit and an equivalent circuit diagram showing a trigger circuit including such portions (portions enclosed by dotted lines), respectively;

FIG. 5 is a view showing the operational range of a flip-flop with respect to a power supply;

FIG. 6 is a view showing a conventional flip-flop driving circuit;

FIG. 7 is a view showing input and output signal waveforms of the circuit shown in FIG. 6;

FIG. 8 is a circuit diagram showing the flip-flop driving circuit according to an embodiment of the present invention; and

FIG. 9 is a view showing input and output signal waveforms of the flip-flop shown in FIG. 8.

Referring to FIG. 1 of the drawings, there is shown a well-known flip-flop arrangement constituted by MIS transistors.

Such a flip-flop uses the gate capacitance of the MIS transistors as a temporary storage element so as to be able to produce binary counter action, and it is greatly advantageous over a binary counter flip-flop constituted by bipolar transistors in that the number of circuit elements can be remarkably reduced. A further advantage of such a flip-flop arrangement is that the manufacture thereof is facilitated in an attempt to assemble it in the form of a semiconductor integrated circuit since it is formed by MIS transistors.

In FIG. 1, T_1 and T_5 represent inverter MIS transistors, respectively, and T_3 and T_6 denote load MIS transistors of which the drains are connected with a DC power source terminal P , respectively. T_4 and T_8 indicate gate MIS transistors of which the gates are connected with a first pulse input terminal i , respectively. T_3 and T_7 represent memory MIS transistors adapted to produce a memory effect with the aid of gate capacitances C_1 and C_2 thereof, respectively, and T_2 and T_9 indicate trigger MIS transistors of which the gates are connected with a second pulse input terminal i' , respectively.

By applying pulses which are 180° out of phase with each other as shown at $band\ ain$ FIG. 2 to the first and second pulse input terminals i and i' respectively, it is possible to obtain at output terminals 0 and $0'$ output pulse signals having a frequency which is one-half the frequency of the input pulse signals as shown at d and e in FIG. 2 respectively. Such a flip-flop is capable of producing binary counter action, and therefore it is possible to form any desired counter, shift register and so forth by cascading such flip-flops in the form of a flip-flop chain.

In an attempt to construct the foregoing flip-flop in the form of a semiconductor integrated circuit arrangement, however, it is essential that care be taken to minimize power consumption. That is, it is required that the operation be able to be performed even if the voltage of the power source V_{DD} is low.

When the voltage of the power source V_{DD} is low, "on" current flowing through the MIS transistors is decreased so that the power consumption in the flip-flop per se is reduced. This is advantageous in that a temperature rise can be prevented from occurring in the semiconductor integrated circuit device. When a chain of such flip-flops is integrated in a single semiconductor substrate, it is necessary to minimize power consumption so as to prevent heat generation, since MIS transistors are integrated in such a single substrate with a high density. To meet such a requirement, the flip-flop should be operated with a low-voltage source.

On the other hand, the above-described flip-flop has such a disadvantage that an input pulse signal voltage V_{IN} for driving the gate MIS transistors T_4 and T_8 must be high.

That is, disadvantageously, that gate voltage of the gate MIS transistors T_4 and T_8 with respect to a reference potential which is needed to render these transistors conductive (such gate voltage will be referred to as threshold voltage) must be made higher (-13 V, for example) than twice the threshold voltage (-6 V, for example) of the memory MIS transistors T_3 and T_7 , since the sources of the gate MIS transistors T_4 and T_8 are connected with the gates of the memory MIS transistors T_3 and T_7 .

The reason is that since P-type regions 32 and 42 constituting the sources of a plurality of transistors T_3 and T_4 and P-type regions 33 and 43 forming the drains thereof are integrally formed in a single N-type silicon semiconductor substrate 31 and the semiconductor substrate 31 is connected with a reference potential source E through a terminal G_2 as shown in FIG. 3, the threshold voltages of the transistors T_4 (or T_2) and T_8 (or T_6) of which the sources S are not connected directly with the reference potential source are influenced by the semiconductor substrate 31 so as to become higher than that of the transistor T_3 (or T_7), as shown in FIGS. 3 and 4. Empirically, a threshold voltage increases substantially in proportion to the square root of the reverse voltage between the substrate 31 and the source S . Therefore, the threshold voltages of the gate transistor T_4 (or T_8) is influenced by the substrate so as to become somewhat higher than twice the threshold voltage of the memory transistor T_3 (or T_7) having the source thereof connected directly with the reference potential source, as described above.

In contrast, the threshold voltages of the trigger MIS transistors T_2 and T_6 are not effected by the substrate 31 and assume a low value (-6 V, for example) because the "on" operation of making the trigger transistor T_2 or T_6 conductive is limited to only when the memory MIS transistor T_3 or T_7 is rendered conductive, although the source of the MIS transistors T_2 or T_6 are connected to the potential source E through the path between the sources and the drains of the memory MIS transistors T_3 and T_6 . Hence, the voltage required to obtain V_{IN} becomes lower than V_{IN} ($\frac{1}{2}$ of V_{IN} , for example).

From the foregoing, it will be seen that the above-described conventional flip-flop circuit is disadvantageous in that the input pulse signal voltage of $\bar{V}_{IN}$ may be low but the input pulse signal voltage of V_{IN} should be high.

Thus, in order to drive such a flip-flop with a low pulse signal voltage $\bar{V}_{IN}$, an attempt has conventionally been made

to provide an inverter circuit 1 before a flip-flop 2 and drive gate MIS transistors T_4 and T_8 by the output of the inverter circuit, as shown in FIG. 6. The FIG. 6 arrangement is designed so that when a low pulse voltage V_{IN} is applied as an input to the inverter circuit 1 having a high voltage source V_{GG} , an inverted high voltage V_{IN} is obtained at an output terminal O_1 to drive the gate MIS transistors T_4 and T_8 .

However, the inverter has found that in such a conventional flip-flop driving method, the possibility occurs that the following erroneous operation is performed by an inverter transistor T_{20} .

By applying a pulse voltage V_{IN} such as shown at *a* in FIG. 7 to the input terminal i_1 of the inverter circuit, a inverted waveform V_{IN} is produced in which a delay is caused in the rising and falling portions thereof as shown at *b* in FIG. 7. The rise time or period of time from a point of time t_1 when the inverter transistor T_{20} is "off" to a point of time t_2 when it is "on" depends upon the product of the "on" resistance on the inverter transistor T_{20} and input capacitance of the flip-flop 2 or the time constant. Such a rise time is so long that the gate MIS transistor T_4 (or T_8) tends to operate simultaneously with trigger MIS transistor T_2 (or T_6) during a time t_{off} (see FIG. 7) when V_{IN} is greater in the negative direction than the threshold voltage E_{th} of the gate MIS transistor T_4 (and T_8), thus resulting in erroneous operation. Such operation will be examined with reference to FIG. 7. It may be considered that at a point of time t_1 , the trigger transistors T_2 and T_6 are rendered conductive so that the states of the transistors T_1 and T_5 are reversed. Assume that the transistor T_5 is switched from nonconducting state to conducting state, i.e., T_1 is switched from conducting state to nonconducting state by the conduction of the trigger transistors T_2 and T_6 at the point of time t_1 . If the gate transistors T_4 and T_8 are turned off immediately at the point of time t_1 , then normal operation will be performed. However, since the transistors T_4 and T_8 are maintained in the "on" state due to the delay of the signal V_{IN} during the time t_{off} , the drain voltage ("off" level voltage) of the transistor T_1 is applied to the gate of the memory transistor T_3 through the gate transistor T_4 during said time t_{off} , so that the transistor T_3 is immediately turned on. On the other hand, at this time, the transistor T_2 is in the conducting state. Thus, the transistor is again returned from its "off" state to its "on" state. That is, the transistor is reversed from "on" state to its "off" state at the point of time t_1 , but it is again returned to its "on" state by a point of time t_4 , thus resulting in erroneous operation.

As a result of such erroneous operation, the operational range of the flip-flop with respect to the supply voltage is reduced. FIG. 5 shows the operational range 10 of the flip-flop 2 (operating portion is shown by oblique lines), with the supply voltage V_{DD} for the flip-flop 2 indicated on the horizontal axis and the supply voltage V_{GG} for the inverter circuit on the vertical axis.

As will be seen from FIG. 5, the range of V_{GG} which can be selected is limited when V_{DD} is lower than -25 V for example, and the flip-flop is stopped from operation when V_{GG} , the level of the output voltage V_{IN} of the inverter is increased up to $-E_2$ as shown by a broken curve at *b* in FIG. 7, so that the time t_{off} is extended as indicated by t'_{off} ($t'_{off} > t_{off}$), thus increasing the possibility of erroneous operation. Conversely, this means that the voltage V_{DD} cannot be made lower than a certain limit determined from the relationship with V_{GG} in case V_{GG} is lower than -35 V for example.

The present invention has been made through experiments and research conducted in view of the fact that the period of time required for permitting the memory MIS transistor to switch from its "on" to its "off" state after applying a pulse voltage to the gate MIS transistor is longer than that for permitting the trigger transistor to switch from its "off" to its "on" state, and it is characterized in that the trigger MIS transistors are driven by the output of a inverter circuit constituted constituted by MIS transistors, and that the inputs of the gate MIS transistors are made common to that of the inverter circuit.

The present invention will be more fully understood from the following description.

FIG. 8 shows an embodiment of the present invention, wherein parts corresponding to those of FIG. 6 are indicated by similar symbols. An inverter circuit 3 provided in accordance with the present invention includes an inverter MIS transistor T_{30} and a load MIS transistor T_{31} , therefor. Output terminal O_2 of the inverter circuit 3 is connected with the gates of the trigger MIS transistors T_2 and T_6 , and the gates of gate MIS transistor T_4 and T_8 are connected with input terminal i_2 of the inverter circuit 3.

Description will now be made of the operation of the present invention. For the simplicity of explanation, it is assumed that a perfect pulse voltage V_{IN} such as shown at *b* in FIG. 9 is obtained at the input terminal i_2 of the inverter circuit 3 in common with the input terminal i for the gate transistors T_4 and T_8 . The pulse voltage is reversed and delayed by the inverter circuit 3 so that such a signal V_{IN} as shown at *a* in FIG. 9 is obtained at the output terminal O_2 of the inverter circuit 3. The inverted signal V_{IN} is imparted to the input of the trigger transistor T_2 and T_6 . Assume that the inverter MIS transistor T_1 of the flip-flop 2 is turned on (hence T_5 is turned off) between points of time t_1 and t_2 in FIG. 9. Then, a voltage V_D is produced at the drain of T_5 , and the drain of T_1 is maintained at a reference potential. At this point, since the gate MIS transistors T_4 and T_8 are conducting, the drain voltage V_D of T_5 is stored at gate capacitance C_2 of the memory MIS transistor T_7 , whereby the latter is turned on. Further, the gate voltage of T_3 is reduced to zero. After T_4 and T_8 are turned off at t_2 , T_2 and T_6 are turned on at t_3 . Thus, with this arrangement, there occurs no such inconvenience as involved in the conventional arrangement (see FIG. 7 *a*, *b*).

Between points of time t_3 and t_4 , the trigger MIS transistors T_2 and T_6 are turned on, so that the inverter MIS transistor T_5 is turned on while T_1 is turned off by the conduction of T_6 and T_7 . Thus, the states of T_1 and T_5 are reversed by the pulse voltage V_{IN} applied to the trigger MIS transistors T_2 and T_6 .

The trigger MIS transistors T_2 and T_6 are still conducting between points of time t_4 and t_5 , and at the point of time t_4 , the pulse voltage V_{IN} is applied to T_4 (and T_8) to turn off the latter. Therefore, it is considered that the possibility may occur that T_3 is turned on while T_7 is turned off. However, the period of time from when V_{IN} is actually applied to the input terminal i to when T_3 is turned on (the sum of the period of time required to turn on T_4 and that required to turn on T_3) becomes longer than the period of time t_{off} indicated in FIG. 9, so that that memory MIS transistor T_3 is turned on and T_7 is turned off after the trigger MIS transistors T_2 and T_6 are turned off at the point of time t_5 . Consequently, there occurs no such erroneous operation that the trigger MIS transistor T_2 and memory MIS transistor T_3 are simultaneously turned on between the points of time t_4 and t_5 .

In accordance with the present invention, it is possible to prevent such erroneous operation as with the conventional arrangements, since the flip-flop is reversed by rendering the trigger MIS transistor conductive after the gate MIS transistors have completely been turned off, subsequently the trigger MIS transistors are again turned off, and thereafter the gate MIS transistors are turned off, as described above.

The operational range 11 is indicated by the broken line in FIG. 5 corresponds to the case where the present invention is applied. From this, it will be seen that in accordance with this invention, the operational range with respect to the supply voltage can be made wider than that of the prior art arrangement, and that operation can be performed even with a low voltage. In this case, the lower limit of V_{DD} corresponds to the minimum value at which the trigger MIS transistors of the succeeding flip-flop can be driven in the circuit arrangement of FIG. 8, and the lower limit of V_{GG} corresponds to the minimum value at which the gate MIS transistors of the succeeding flip-flop can be operated in the circuit arrangement of FIG. 8.

Therefore, the present invention can be effectively applied to applications in which the flip-flop chain is constituted by the use of a multiplicity of flip-flops 2. With a flip-flop chain, it is required that the output pulse voltage V'_{IN} available at the output terminal O' of a flip-flop 2 be converted to the high pulse voltage V_{IN} between the flip-flop stages since the succeeding flip-flop should be driven by said output voltage. To meet this requirement, the inverter circuit 1 and the inverter circuit 3 according to the present invention are provided between a first flip-flop stage and a second flip-flop stage. The resulting flip-flop chain can be satisfactorily operated with a lower value for the supply voltage V_{DD} of the flip-flop than in the case of the conventional device, as will be seen from FIG. 5. Thus, it will be appreciated that power consumption in the flip-flop chain can be reduced, and that the flip-flop can easily be constructed by the integrated circuit technique.

To sum up, the present invention is characterized in that gate MIS transistors are driven by an input pulse voltage of the inverter circuit and trigger MIS transistors are driven by the output pulse voltage of the inverter circuit. Of course, this invention may also be applied to a flip-flop 2 using a single trigger MIS transistor T'_2 as shown in FIG. 10.

What is claimed is:

1. In combination, a flip-flop constituted by cross-connecting the inputs and outputs of first and second inverter stages each comprising a field effect transistor and load impedance means;

a first trigger circuit connected with the output of said first inverter stage and the input of said second inverter stage, said first trigger circuit being constituted by a first insulated gate field effect transistor, a second insulated gate field effect transistor having a path between the source and the drain thereof connected between the drain of said first transistor and the output of said first inverter stage, and a third insulated gate field effect transistor having the path between the source and the drain thereof connected between the gate of said first transistor and the output of said first inverter stage;

a second trigger circuit connected between the output of said inverter stage and the input of said first inverter stage, said second trigger circuit being constituted by a fourth insulated gate field effect transistor, a fifth insulated gate field effect transistor having the path between the source and the drain thereof connected between the drain of said fourth transistor and the output of said second inverter stage, and a sixth insulated gate field effect transistor having the path between the source and the drain thereof connected between the gate of said fourth transistor and the output of said second inverter;

a third inverter stage comprising a transistor and a load impedance means, the input of said third inverter stage being connected in common with the gates of said third and sixth transistors and the output thereof being connected in common with the gates of said second and fifth transistors; and

a pulse signal source connected with the input of said third inverter stage.

2. The combination according to claim 1, wherein a fourth inverter stage is connected between the input of said third inverter stage and said pulse signal source, said fourth inverter stage is constituted by a transistor, load impedance means thereof and a first power source, and a second power source is connected in common with said first, second and third inverter stages.

3. The combination according to claim 2, wherein all the impedance means are constituted by insulated gate field effect transistors, and the transistors constituting the first, second and third inverters are insulated gate field effect transistors.

4. In combination, a flip-flop constituted by cross-connecting the inputs and outputs of first and second inverter stages each comprising a field effect transistor and a load impedance; a first and second insulated gate field effect transistors each

having the drain thereof connected with the output of the

first inverter stage and the input of the second inverter stage, the gate of the second transistor being connected with the source of the first transistor;

5. third and fourth insulated gate field effect transistors each having the drain thereof connected with the output of the second inverter stage and the input of the first inverter stage, the gate of the fourth transistor being connected with the source of the third transistor;

10 a fifth insulated gate field effect transistor having the drain thereof connected with the sources of said second and fourth transistors;

15 a third inverter stage comprising a transistor and load impedance means, the input of said third inverter stage being connected in common with the gates of said first and third transistors and the output thereof being connected with the gate of said fifth transistor; and

20 a pulse signal source connected with the input on said third inverter stage.

5. A combination according to claim 4, wherein a fourth inverter stage is connected between the input of said third inverter stage and said pulse signal source, said fourth inverter stage comprising a transistor, load impedance means therefor and a first power source, and wherein a second power source is connected in common with said first, second and third inverter stages.

25 6. The combination according to claim 5, wherein all the impedance means are constituted by insulated gate field effect transistors, and the transistors which constitute the first, second and third inverters are insulated gate field effect transistors.

30 7. The combination comprising a first and a second switching means; means interconnecting said first and second switching means to form a flip-flop circuit; a first and a second memory circuit connected to said first and second switching means, respectively, each of said first and second memory circuits comprising a first insulated gate-type field effect transistor for memorizing the state of said flip-flop circuit and a second insulated gate-type field effect transistor having two output terminals, one of said output terminals of said second transistor being connected to the gate electrode of said first transistor;

35 40 45 a trigger circuit coupled to said first and second memory circuits for controlling the state of said flip-flop circuit, said trigger circuit comprising at least one third insulated gate-type field effect transistor connected in series with said first transistor of said respective memory circuits; an inverter circuit including a fourth insulated gate-type field effect transistor having two output terminals and a load impedance means therefor; means for electrically connecting the gate electrode of said fourth transistor to the gate electrodes of said second transistor of said respective memory circuits; means for electrically connecting one of said output terminals of said fourth transistor to the gate electrode of said at least one third transistor; and means for supplying a pulse signal to the gate electrode of said fourth transistor.

40 45 50 55 60 65 8. The combination according to claim 7, further comprising a second inverter circuit including a fifth insulated gate-type field effect transistor having two terminals and a second load impedance means therefor, and means for connecting the gate electrode of said fourth transistor with one of said fifth transistor, whereby said pulse is applied to the gate electrode of said fourth transistor through said second inverter circuit.

9. The combination according to claim 8, wherein said flip-flop circuit and said first inverter circuit are operated by a first voltage-supplying source and said second inverter circuit is operated by a second voltage-supplying source having a voltage value higher than said first voltage-supplying source.

70 75 10. The combination comprising a first and a second switching means; means interconnecting said first and second switching means to form a flip-flop circuit; a first and a second circuit means for controlling the state of said flip-flop circuit connected to said first and second switching means, respec-

tively, each of said circuit means comprising a first, a second and a third insulated gate-type field effect transistor, each transistor having a gate electrode and two output terminals, means for connecting said first and second transistors in series, means for connecting the gate electrode of said first transistor with one of said output terminals of said third transistor; an inverter circuit means having an input terminal and an output terminal; means for electrically connecting said input terminal of said inverter circuit means with said gate electrodes of said third transistors; means for electrically connecting said output terminal of said inverter circuit means with said gate electrodes of said second transistors; and means for supplying a control signal to said input terminal of said inverter circuit means.

11. The combination as claimed in claim 10, wherein said control-signal-supplying means comprises a second inverter circuit means having an input terminal and an output terminal and means for connecting said output terminal of said inverter circuit means to said input terminal of said first inverter circuit means, whereby said control signal is applied to said input terminal of said first inverter circuit means through said second inverter circuit means.

12. The combination according to claim 11, further including means for supplying a DC voltage to said second inverter means which is higher than the voltage applied to said flip-flop circuit and said first inverter circuit means.

13. The combination according to claim 11, wherein each of said first and second inverter circuit means comprises an insulated gate-type field effect transistor and a load impedance means.

14. The combination comprising, a first, a second and a third insulated gate-type field effect transistor each having an input terminal and two output terminals; means for connecting the output terminal of said first transistor to one of said output terminals of said third transistor; means for connecting one of said output terminals of said first transistor to one of said output terminals of said second transistor; means for supplying an operating source voltage between the other of said output terminals of said first transistor and the others of said output terminals of said second and third transistors through an impedance means; means for supplying a first pulse signal to said input terminal of said third transistor; and means for supplying a second pulse signal to said input terminal of said second transistor, said second pulse signal being inverted and delayed in phase with respect to said first pulse signal, wherein said first and second pulse-signal-supplying means comprise a

fourth insulated gate-type field effect transistor having an input terminal and two output terminals, means for supplying a second operating source voltage between said two output terminals through a second impedance means, means for connecting one of said output terminals of said fourth transistor to said input terminal of said second transistor, means for connecting said input terminal of said fourth transistor to said input terminal of said third transistor and means for impressing an input signal on said input terminal of said fourth transistor.

15. The combination comprising a first, a second and a third insulated gate-type field effect transistor, each having an input terminal and two output terminals; means for connecting the input terminal of said first transistor to one of said output terminals of said third transistor, means for connecting one of said output terminals of said first transistor to one of said output terminals of said second transistor; means for supplying an operating source voltage between the other of said output terminals of said first transistor and the others of said output terminals of said second and third transistors through an impedance means; means for supplying a first pulse signal to said input terminal of said third transistor; and means for supplying a second pulse signal to said input terminal of said second transistor, said second pulse signal being inverted and delayed in phase with respect to said first pulse signal, wherein said first and second pulse-signal-supplying means comprise a fourth and a fifth insulated gate-type field effect transistor, respectively, each having an input terminal and two output terminals, means for connecting said input terminal of said fourth transistor to one of said output terminals of said fifth transistor, means for connecting said input terminal of said fifth transistor to one of said output terminals of said fourth transistor, means for connecting said input terminal of said third transistor to said input terminal of said fourth transistor, means for supplying a second and a third operating source voltage between said two output terminals of said fourth and fifth transistors through a second and a third load impedance, respectively, and means for impressing an input signal on said input terminal of said fifth transistor.

16. The combination according to claim 15, wherein the value of said third operating source voltage for operating said fifth transistor is larger than that of said second operating source voltage for operating said fourth transistor and that of said first operating source voltage for operating said first, second and third transistors.
